UNITED STATES PATENT OFFICE.

JOHN C. TURNER AND FORREST H. HARTZELL, OF DAYTON, OHIO, ASSIGNEES TO THE SCHIEBLE TOY & NOVELTY COMPANY, OF DAYTON, OHIO, A CORPORATION OF OHIO.

SHEET-METAL WHEEL.

1,200,276.

Specification of Letters Patent. Patented Oct. 3, 1916.

Application filed September 8, 1914. Serial No. 860,559.

To all whom it may concern:

Be it known that we, JOHN C. TURNER and FORREST H. HARTZELL, citizens of the United States, and residing at Dayton, in the county of Montgomery and State of Ohio, have invented a new and useful Improvement in Sheet-Metal Wheels, of which the following specification is a full disclosure.

10 Our invention relates to an improvement in sheet metal wheels, especially applicable to toys.

An object of the invention is to provide a wheel in which the hub, spokes and rim are 15 integrally formed from a sheet of metal, each having specific characteristics, the hub portion being dished or embossed, the spokes of a semi-circular, curved or corrugant cross-sectional contour, and an embossed circumferential rim terminating in a transverse tread-margin.

Another object of the invention is to provide a wheel of two sheet metal members, the one to comprise a unit member of hub, 25 spokes and rim, and the second a hub member, both having concentric holes or apertures in alignment to receive an axle, and provide two bearing surfaces for the axle, the hub member of roughened, scalloped or 30 undulating contour, adapted to circumferentially seat and coincidentally intermesh with the reverse side of the unit member and be laterally secured thereto by fastening tangs integral with one of said members, 35 and bent to clasp upon the second.

Various other objects and features of the invention relate to structural details, and 40 also possess combined architectural and mechanical characteristics in the production of a miniature facsimile of an automobile wheel, all of which will be more fully set forth in the description of the accompanying drawing disclosure embodied in a preferred form of the invention, and which 45 forms a part of this specification, and in such drawings like characters of reference denote corresponding parts throughout the several views of which:—

Figure 1 is an inside plan view of our improved toy wheel. Fig. 2 is a section on line 50 2—2, Fig. 1, and Fig. 3 is an enlarged section on line 3—3, Fig. 1.

The invention herein is primarily directed to a sheet metal wheel for toy vehicles, but, it is apparent however, that its

construction renders its use possible to other fields, and is thus comprehended. Its construction offers greater rigidity and strength than ordinarily required for the class of sheet metal toys to which the wheels are applied, and which is accomplished without increasing the cost of manufacture over the present known types of sheet metal toy wheels. It offers ease and convenience in assemblage, and presents, from a design or ornamental view, marked features of similarity from a side elevation of a miniature facsimile of an automobile wheel, and when applied to a representative automobile toy materially adds to its attractiveness and selling value.

The architectural characteristics in the miniature facsimile representation of an automobile wheel is enlarged in its scope so as to possess mechanical qualifications, adding rigidity to the wheel and providing devices for securing a hub piece rigidly upon the rear or off-side of a unit wheel member. The unit wheel member and hub piece have concentric holes in alignment to receive an axle 20 and provide two supporting surfaces therefor. As set forth, the wheel unitarily is composed of two members, a unit wheel member, and a hub member, the unit wheel member integrally combining and forming from a sheet metal blank by a process of stamping a central hub portion 1, embossed or dished toward the finish side of the wheel and apertured at its axis 2 to receive an axle. The intermediate portion of said member is divisionally apertured circumferentially around the hub portion to give individuality to the spokes 3. The spokes 3 are of semicircular or U-form in cross section possessive of corrugant functions, as well as 25 imparting a rounded spoke effect ornamenteally from the finish side of the wheel. It also provides recesses or pockets on the off-side or surface of the wheel, which, together with the peripheral surface of the hub intervening the spokes axially presents an undulating circumferential outline to receive the scalloped or coincident contour of the supplemental hub member 5.

6 represents the felly portion of the wheel 30 having the sectional margins 7 at the spoke apertures 8 bent toward the off-side of the wheel, which margins are in respective continuity with the inturned spoke margins, presenting a rounded inner periphery of 35

the felly from the finish side of the wheel. From the felly portion the wheel member is pressed convexly in cross-section or embossed circumferentially to represent the 5 tire portion 9, which terminates in a transverse rim or tread-margin 10. This tread-margin 10 extends rearwardly to a plane with the remainder rearward projections of the wheel on the off surface or side, which 10 gives the wheel a wide tread, adding to the ornamental effect of the wheel, conceals the off-side; and also materially adds to its physical value in locomotive toys, inertia wheel operated, wherein the inertia wheel 15 axle is frictionally engaged upon the periphery of the wheel and the tread-margins further enhanced for its particular usage, by reason of its roughened peripheral surface, due to the compression of the metal in 20 its stamping operation.

The hub member 5 provides a supplemental hub extension from the off-side of the wheel, and is formed from a blank having a scalloped or undulating contour, with the 25 central portion of the blank embossed or dished, and provided with an axial aperture 11, so that when applied to the unit wheel member its embossed portion projects oppositely from that of the hub portion 1, to 30 relatively space the apertures in concentric alignment, and provide two axle contacting or supporting surfaces.

The hub member is rigidly secured to the off-side of the unit member by engaging or 35 seating the teeth 13 of the hub member formed by its roughened or undulating contour respectively into the spoke recesses, and fastening said member laterally in position by the tangs 14 formed integral with the 40 unit member and intermediate of the spokes, which tangs are bent backwardly and overlappingly upon said hub member 5. This hub member, therefore, is secured both against

lateral and axial displacement, and is substantially unitarily combined with the unit 45 member without the use of auxiliary fastening means.

Having thus described our invention, we claim as new and desire to secure by Letters Patent of the United States:—

1. A sheet metal wheel comprising a wheel member having spokes of a cross-sectional formation to provide recesses upon one side, a hub member of a contour adapted to engage into said spoke recesses, and fastening tangs projecting from one member and bent to clasp over the second member for connecting the same.

2. A wheel of the character disclosed, combining a unit sheet metal wheel member having an apertured hub portion, spokes, rim, and fastening tangs intermediate the spokes at the hub circumference, and an apertured hub member having a roughened or undulating contour adapted 60 to register with the irregularities in the surface of the off-side of said unit member and rigidly secured thereto by laterally bending the said tangs to overlap thereon.

3. A sheet metal wheel comprising a 70 member having spokes of a cross-sectional formation to provide recesses upon one side, a hub member of a contour adapted to register with said spoke recesses for non-revolubly mounting one member upon the 75 other and means for securing said members together.

In witness whereof, we hereunto subscribe our names, as attested by the subscribing witnesses.

JOHN C. TURNER.

FORREST H. HARTZELL.
